DISPENSING CLOSURE

Robert E. Hazard, North Kingstown, R.I., assignor to Polytop Corporation, Slatesville, R.I., a corporation of Massachusetts

Filed Oct. 23, 1968, Ser. No. 14,145

Term of patent 14 years

Int. Cl. D9—02

U.S. Cl. D9—275

FIG. 2.

FIG. 3.

FIG. 4.

FIG. 5.

FIG. 1.

FIG. 6.

FIG. 1 is a perspective view of a dispensing closure embodying my new design, with a portion of a container being shown in broken lines for illustrative purposes only;

FIG. 2 is a top plan view on an enlarged scale;

FIG. 3 is a front elevational view thereof;

FIG. 4 is a side elevational view, the opposite side being a mirror image of the side shown;

FIG. 5 is a rear elevational view; and

FIG. 6 is a bottom plan view.

I claim:

The ornamental design for a dispensing closure, as shown and described.
